UNITED STATES PATENT OFFICE.

SECONDO L. CASELLA, OF NEW YORK, N. Y., ASSIGNOR TO CONRAD HUBERT, OF NEW YORK, N. Y.

ELECTRODE-MAKING MACHINE.

1,185,177.

Specification of Letters Patent. Patented May 30, 1916.

Application filed July 3, 1913. Serial No. 777,157.

To all whom it may concern:

Be it known that I, SECONDO L. CASELLA, a citizen of the United States, residing in the borough of Manhattan, city of New York, in the county of New York and State of New York, have invented certain new and useful Improvements in Electrode-Making Machines, of which the following is a specification, reference being had therein to the accompanying drawings, forming part thereof.

My invention relates to machines for making electrodes for voltaic cells, and machines embodying my invention are particularly adapted for making the positive or depolarizing electrode of cells of the Leclanche type, such, for example, as those shown and described in the United States Letters Patent to Albrecht Heil, No. 1,028,354, of June 4, 1912. Such electrodes have a mass of depolarizing material surrounding the carbon rod and incased in a porous bag suitably secured about the depolarizing material. The process of arranging the depolarizing mass about the carbon rod has heretofore been manually performed and has been slow and laborious, and has added materially to the cost of producing the cells.

My invention aims to provide a machine which will perform this process automatically, speedily and at a minimum of cost.

Other objects of my invention are simplicity and inexpensiveness of construction, and convenience and reliability of operation.

Still other objects and advantages of my invention will appear from the following description.

My invention includes means for automatically performing a series of operations upon a mass of depolarizing material in a mold, as, for example, first compacting the material in the mold, then perforating the compacted mass, then inserting a carbon rod or other electrode into the perforation, and finally ejecting the completed electrode from the mold.

In the preferred embodiment of my invention, the machine is provided with a plurality of molds in a table, and the machine is constructed and arranged to perform the successive plurality of operations upon the material in the molds, whereby one of the several operations is performed upon the material in each mold every time

that the machine is operated. More particularly the operation of the machine is controlled by the movement of the table to bring the molds successively into position to have the various operations performed upon them.

My invention also comprehends various other features of construction, and details, arrangements and combinations of parts, as will hereinafter more fully appear.

I shall now describe the embodiment of my invention illustrated in the accompanying drawings, and shall thereafter point out my invention in claims.

Figure 1 is a front elevation of a complete machine embodying my invention. Fig. 2 is a rear elevation of the same. Fig. 3 is a horizontal section of the same on an enlarged scale, taken on line 3-3 in Figs. 1 and 2, looking down and showing the table and slotted guide sleeve thereon in plan, the wooden top for the table and the molds being omitted. Fig. 3^a is a detail of the rotational locking means for the table, taken on line 3^a-3^a of Fig. 3. Fig. 3^b is a detail in elevation of the table and underneath parts as viewed from the right in Fig. 3, one handle being removed for clarity of illustration. Fig. 3^c is a detail in rear elevation of the upper end of the clutch-operating rod and operating cam, the guide sleeve for the operating rod being in section. Fig. 4 is a central vertical section taken through the machine on a plane corresponding to the line 4-4 of Fig. 3, looking toward the right. Fig. 5 is a similar view taken on a plane corresponding to the line 5-5 of Fig. 3, looking toward the rear. Fig. 6 is an elevation, partly in section, of the lower part of the machine, showing the motive mechanism for the machine. Fig. 7 is an enlarged detail in sectional elevation of the perforating head, appearing at the top and left in Figs. 1 and 5 and at the right in Fig. 2. Fig. 8 is an enlarged detail in elevation of the ratchet mechanism for intermittently actuating the feeding wheel in the hopper, as appears in Fig. 4 in the upper portion at the left.

The illustrated machine has a rotative table or turret 1 of general circular shape with four peripheral extensions, as shown in plan in Fig. 3, and mounted upon a hollow standard 2 provided with a suitable base 3. The table 1 preferably has an an-

nular top 4 of wood or other material which will not be corroded by the depolarizing material, and this wooden top rests upon and is secured to the table 1, which is preferably of suitable metal, such as steel. The table is provided with four similar substantially cylindrical open bottom molds 5^a, 5^b, 5^c and 5^d arranged ninety degrees apart, and provided with mouths slightly elevated above the plane of the table, as shown. The vertically reciprocative shaft or rod 6, about which the table 1 rotates, bears in the top 7 of the standard 2 and, on its upper end above the table, carries four operating heads arranged ninety degrees apart and adapted to operate simultaneously upon the material in the respective molds, the four heads extending out from a common collar 8 fixed to the shaft 6. These four heads will now be described in the order of their operation.

The first or compressing head, which is shown at the right in Fig. 4 and at the front in Fig. 1, comprises a wooden plunger 9 which is slidable through a guide sleeve 10 carried by a supporting arm 11 extending up from the standard 2. The plunger 9 slides freely through a hole in a horizontal portion of an arm 12 carried by the collar 8, and weights 13 rest upon an adjustable collar 14 on the upper end of the plunger 9. The plunger 9, is therefore, held by gravity with the collar 14 resting upon the arm 12, and as the arm 12 is lowered with the shaft 6, the plunger 9 follows it, and, in the position of the parts shown in Fig. 4, enters the mold 5^a and compresses the material in the mold. The extent of this compression depends upon the number of weights 13, while the plunger is positively carried upward by the arm 12 bearing under the collar 14.

To assist the operator in arranging sufficient depolarizing material over the mouth of the mold 5^a, a wooden backing or form 13^b of U-shape may be provided which is above the mouth of the mold, occupying the position of the mold 5^a in the drawings, and which is attached by an arm 14^a to the sleeve 10, as shown. As the shaft 6 descends, the plunger 9 presses this material which is over the mouth into the mold 5^a and compresses it the required extent. A block 13^a on the standard is underneath the mold 5^a in this position of the table, and serves as a bottom for the mold 5^a. The second operation consists in perforating the material thus compressed for the reception of the carbon rod. In the position of the machine shown in the drawings, this operation is performed in the mold 5^b by the perforating head. This head, which is shown at the left in Figs. 1 and 5, and in detail in Fig. 7, comprises a hollow guide head 14^a integral with an arm 15 extending out from the collar 8, and a plunger rod 16 is adjustably secured at its upper end

by a set screw 17 in an externally screw-threaded collar 18 which screws into a cap 19 on the top of the guide head 14^b. The lower end of the plunger rod 16 is of wood and is reduced in diameter to that of the carbon rod of the electrode, this reduced lower end fitting into the lower end of the larger portion, as shown. Surrounding the plunger rod 16 is a sleeve 20, which is provided with a wooden lower end, as shown, and screws at its upper end upon a bearing nut 21. A coiled spring 22 surrounds the plunger rod 16 and bears at its upper end against the collar 18 and at its lower end against the bearing nut 21, and tends to push the sleeve 20 outwardly relative to the plunger rod, while permitting it to yield relative to the rod. The outward movement of the sleeve relative to the rod is limited by an adjustable abutment member 23, which has an angular portion extending through slots in the guide head 14^b and sleeve 20 and bears underneath the nut 21. The abutment member 23 is slotted, as shown, and is secured by two screws to the guide head 14^b. The slot in the abutment member permits of its adjustment longitudinally of the guide head 14, and the extent to which the spring 22 is permitted to move the sleeve outwardly relative to the plunger rod is thereby adjusted.

In practice, the abutment member is adjusted so that the lower ends of the sleeve 20 and the plunger rod 16 are substantially even. As the shaft 6 descends, the sleeve 20 and rod 16 engage the top of the compacted material in the mold simultaneously, and the further downward movement of the sleeve is thereafter prevented, the spring yielding to permit the rod to move down independently of the sleeve. The compressed material is thus perforated, a hollow block 24 on the standard serving as a bottom for the mold 5^b and permitting the displaced material to fall down through the hollow center of the block. As the shaft 6 ascends, the plunger rod 16 is retracted, but the spring 22, being under compression, holds the sleeve 20 against the material in the mold until the plunger rod is fully withdrawn, and the rod is thus prevented from breaking the compressed material due to its adhesion to the material.

The third operation consists in inserting a carbon rod into the perforation which is formed by the second head, and this third operation is performed by the third or carbon-inserting head shown at the left in Fig. 4, and in the position of the table shown in the drawings, this operation is performed upon the material in the mold 5^a. The carbon rods are carried in a hopper 25 which is supported on the upper end of a hopper-supporting arm 26 extending up from the standard 2, and provided with an angular

branch 27 (see Figs. 4 and 8), the horizontal member of which is provided with an opening through which the carbons may pass. The hopper 25 has an open bottom, and a carbon feeding wheel 28 is rotatively mounted in the bottom of the hopper, being pinned to a shaft 29, which bears at one end in the hopper-supporting arm 26 and at its other end in the upright member of the branch 27. This wheel 28 is provided with a plurality of carbon-receiving grooves about its periphery and, as the wheel 28 is rotated, the carbons are carried around in the grooves and dropped out through the open bottom of the hopper. The carbon-inserting head comprises the hollow head 30 on the outer end of an arm 30' extending out from the collar 8, and in this head 30 is adjustably secured a vertical push rod 31, which is disposed axially over the mold 5^e. To impart the intermittent rotative actuations to the wheel 28 to feed the carbons at the desired time, means are employed under the control of the movement of the head 30 which are shown in detail in Fig. 8, and which will now be described. A ratchet wheel 32 is fixed on the shaft 29 and a pawl-carrying arm 33 is loosely pivoted upon the shaft 29 and carries the pawl 34, which engages in the teeth of the ratchet 32, being held in engagement by a flat spring 35. An outwardly extending arm or finger 36 is carried by the vertical reciprocative head 30 and is arranged underneath the outer or free end of the pawl-carrying arm 33. A coiled spring 37 is attached to the outer end of the arm 33 and is suitably anchored at its lower end to the branch 27 or other convenient stationary anchoring means, and this spring 37 tends to draw the arm 33 down, the downward movement of the arm 33 being limited by a stop 38 on the branch 27. As the head 30 is lowered, the arm 36 is carried down with it and the pawl-carrying arm 33 is rotated downwardly by the spring 37 until the stop 38 is engaged. The parts are so designed that this is just far enough to permit the pawl 34 to engage another tooth in the ratchet 32 and, as the head is again raised, the arm 36 engages underneath the pawl-carrying arm 33 and rotates it up against the tension of the spring 37, thereby rotating the ratchet 32 one tooth. The number of the carbon-receiving grooves in the periphery of the feeding wheel 28 is the same as that of the teeth in the ratchet 32, and, therefore, each individual actuation of the ratchet 32 rotates the wheel 28 one groove and releases one carbon.

Underneath the hopper 25 is arranged a chute 39 secured to a plate 40, which is attached to an inwardly extending bracket 41 on the hopper-supporting arm 26. As the carbons are released from the wheel 28, they

fall down upon this chute 39 and slide down this chute until their lower ends rest upon the flat spring 42, which is secured to the under side of the chute 39 and is bent so that its lower end extends in a horizontal plane over the mold 5^e. The plate 40 has an angular portion 42^a extending in front of the chute 39 and this front plate 42^a serves as a stop for the carbons. An arcuate slot 43 is provided in the plate 40 underneath the lower end of the chute 39 and a pin 44 projects inwardly into this slot and is carried by a lever 45 which is pivoted at its upper end to an extension 46 on the branch 27 of the hopper-supporting arm 26. A coiled spring 47 is secured at one end to the lever 45 and at its other end to the front plate 42 and tends to pull the lever 45 over so as to bring the pin 44 to the front end of the slot 43 and thus straighten up the carbon which is resting upon the spring 42. A cam 48 on the lever 45 co-operates with the cam 49 on the head 30 and holds the lever 45 in retracted position when the head 30 is raised, while permitting the lever 45 to be drawn forwardly by the spring 47 when the head 30 is depressed. Thus the pin 44 straightens up the carbon and arranges it in line with the push rod 31 directly over the perforation in the material in the mold 5^e. It will now be clear that a carbon is released from the wheel 28 each time that the head 30 ascends and as the head 30 descends this carbon is first straightened up by the inward movement of the pin 44 and is then engaged by the push rod 31 and is pushed off the end of the spring 44 and into the perforation of the material in the mold 5^e. A hollow block 50 on the standard is disposed underneath the mold 5^e in this position of the table and serves as a bottom and thus prevents the material from being pushed out of the bottom of the mold as the rod is inserted.

The fourth and final operation of the machine is performed by the ejecting head, which is shown at the right in Figs. 1 and 5 and at the left in Fig. 2. This comprises merely the hollow head 51 on the arm 52 extending radially outward from the collar 8, in which head is secured a hollow wooden ejecting plunger 53 so arranged that in the downward movement of the head 51 the carbon in the electrode in the mold 5^d, which mold is underneath the ejecting head in the position of the machine shown in the drawings, enters into the hollow interior of the ejecting plunger 53, while the bottom of the plunger presses against the depolarizing material and forces the electrode out of the bottom of the mold, where it drops into a suitable receptacle (not shown). To thus reciprocate the shaft 6 and the heads carried by it, the lower end of the shaft is connected by a connecting rod 54 to the

crank 55 on the crank shaft 56, which shaft has its bearings in the lower part of the standard 2. Means are provided for guiding the shaft 6 during its vertical reciprocation to prevent any rotational movement of the shaft. On the upper side of the table 1 there is provided about the shaft 6 a slotted guide sleeve 57, which is provided with four vertical slots 58, and keys 59 in 10 the shaft 6 enter into these guide slots 58 as the shaft is reciprocated. A similar slotted guide is also provided in the lower part of the standard 2 beneath the table and a key 60, which extends through the shaft 6, moves in this slotted guide and rigidly holds the shaft 6 against any tendency to rotate. To prevent the depolarizing material from getting in contact with the metallic guide sleeve 57, a collapsible fiber 20 shield is provided, comprising an outer stationary fiber sleeve member 61 carried by the wooden top 4 of the table, and an inner telescopic fiber sleeve member 62 carried by the collar 8 on the shaft 6. The actuation 25 of the shaft 6 is controlled by the rotational movement of the table 1. On the underside of each of the four peripheral extensions of the table 1 there is provided a cam, these cams being numbered respectively 63, 64, 65 30 and 66. A power driven pulley 67 is loosely mounted upon the crank shaft 56, and to clutch this pulley to the crank shaft 56 any suitable single rotation clutch mechanism may be provided, such, for instance, as that 35 shown in the patent to Herbert E. Marshall, No. 945,565, of January 4, 1910. This clutch mechanism forms no part of my invention and is conventionally indicated in the drawing by the reference numeral 68. An actuating rod 69 extends up from this clutch mechanism through a bearing 70 provided 40 for it in the lower part of the hopper-supporting arm 26 and has on its upper end a slidable cam member 71, which fits in the bearing 70 and is provided with a cam face 45 on its upper end arranged to coöperate with the cams 63, 64, 65 and 66. The rod 69 and the cam member 71 are normally maintained in elevated position by a thrust spring 72, 50 which is arranged in a suitable case on the base 3 and bears against the lower end of a rod 73 on the under side of the clutch mechanism, which rod extends into the cylindrical case for the spring 72. In this elevated position of the clutch mechanism, the pulley 67 is disconnected from the crank shaft 56 and the mechanism is so constructed that, as the rod 69 is depressed, the clutch is thrown in for a single rotation 55 60 and is then automatically thrown out again. In operation, the table 1 is rotated one step until a cam on the table trips the clutch by riding over the cam member 71 on the clutch rod 69 and depressing this rod, and thus 65 causing the pulley 67 to be connected to the

crank shaft 6 and to impart one complete actuation to the shaft 6 and the heads carried thereby.

In Fig. 3^c is shown the relative positions of the cams 65 and 71 after the cam 65 has passed the cam 71 and tripped the actuating mechanism. The cam 71 is immediately returned to its elevated position by the spring 72 and by its engagement against the rear of the cam 65 serves to lock the table against 70 backward rotation. Any back lash is thereby prevented, but, as an additional precaution, further means may be provided to prevent back lash, such as shown in detail in Fig. 3^a. A rearwardly extending 75 lever 74 is pivoted between two upright arms 75 on the sleeve-supporting arm 11, and a cam 76 is provided on the upper side of the rear end of this pivoted lever 74 in position to be engaged by a cam on the 80 under side of the table as the table is rotated. The rear end of the lever 74 is resiliently held in elevated position by a coiled spring 77, which is attached to the front end of the lever 74 and is suitably anchored 85 at its lower end to the sleeve-supporting arm 11. As the cam on the table rides over the cam 76, it depresses the front end of the lever 74 against the tension of the spring 77, and after the cam on the table 90 rides off the cam 76, the latter is immediately elevated, and the rear end of the two cams are shaped to abut against each other and prevent any backward movement of the table. In Fig. 3^a the cam 64 is shown as 95 having just ridden over the cam 76 and as locked thereby against backward movement. If it is found that the clutch-actuating cam 71 is sufficiently effective in preventing back 100 lash, this additional mechanism may be dispensed with.

To facilitate the rotation of the table 1, the table is provided with four equally spaced handles 78^a, 78^b, 78^c and 78^d. These handles are attached to plates 79 which are pivoted underneath the table on vertical axes 80 and these handles are resiliently held in their rearmost position of rotation by spring-pressed bolts 81 arranged underneath the table and bearing against lugs 82 110 on the left side of the respective handle plates 79. This position of rotation under the influence of the spring bolts 81 is limited by a set screw 83 in a lug 84 on the right side of the handle plates, which bears 115 against the edge of the table 1. The handle plates 79 carry an abutment member 85 on their right side which is set into a groove in a thickened portion on the under side of the plates, and between the third and fourth 120 operating heads there is provided a stop 86 which, in the construction shown, is a stationary flat piece set in a slot on the top of the standard underneath the table in position to engage the abutment 85 on the par- 125 130

ticular handle which is between the third and fourth heads. In the position of the machine shown in the drawings, the handle 78^a is in this position and its abutment 85⁵ is in engagement with the stop 86. These parts are so located that the abutment engages the stop just as the respective cam rides over the clutch-tripping cam 71, and the table is thereby locked against both forward and backward rotation. It will be apparent that this position must be determined with great exactness in order that the operating plungers may enter their respective molds as the heads descend.

15 In operation, the operator stands by the corner of the machine occupied by the handle 78^a in the position shown in the drawings. A quantity of depolarizing material is preferably located on a table immediately adjacent the rotative table and the operator draws the material from this quantity on the adjacent table into the form or backing 13^b, keeping this form full of material. Assuming that the machine has operated in 20 the position shown in the drawings, and referring particularly to Fig. 3, the mold 5^a (see Figs. 1 and 5) is empty, the material in the mold 5^a (see Figs. 1 and 4) is compressed, the material in the mold 5^b (see 25 Figs. 1 and 5) is perforated, and the material in 5^c (see Fig. 4) has received its carbon. The form 13^b is full of material and the operator grasps the handle 78^a and pulls it to the left, rotating the table clockwise 30 as viewed in Fig. 3, as indicated by the arrow at the handle 78^a. The handle 78^a first rotates independently of the table and against the tension of the spring-pressed bolt 81 until the abutment 85 escapes by the stop 86. The table is then released for rotation 35 and is rotated another step to the left and until the abutment 85 of the handle 78^a strikes the stop 86. Just before this occurs, the cam 64 will have tripped the 40 clutch-actuating cam 71 and the machine heads will descend. The table is in this position tightly locked against forward rotation by engagement of the abutment 85 of the handle 78^a against the stop 86 and 45 against backward rotation by the engagement of the cam 64 against the cam 71 and by the engagement of the cam 63 against the cam 76. The mold 5^a is now underneath the first head and the plunger 9 descends 50 and presses the material from the form 13 into the mold 5^a and at the same time the other three operations are performed by the other three heads upon the material in the other molds, as above described. This 55 operation is repeated, and with each actuation of the machine each of the four operations is performed. As above explained, each actuation of the machine comprises the movement of the heads down and their return 60 to elevated position, and the clutch is then 65

automatically released and the heads are not again depressed until the table is again rotated another step and the clutch mechanism is again tripped. The table 1 is retained upon the top part 7 of the standard 70 2 by a ring 87 (see Fig. 5) of brass or other suitable material, which surrounds the upper part of the head 7 and has its top inwardly flanged about a collar on the lower part of the table. A cylindrical fiber shield 75 88 is carried by the table on its under side and surrounds the ring 87 and prevents the depolarizing material from getting into the bearing of the table and corroding the metal parts.

80 It is obvious that various modifications may be made in the construction shown in the drawings and above particularly described within the principle and scope of my invention.

I claim:

1. An electrode-making machine comprising a mold, means for compressing depolarizing material in the mold, means for axially perforating the compressed material in 90 the mold, means for inserting an electrode in the perforation, and means for ejecting a completed electrode from the mold.

2. An electrode-making machine comprising a mold, a compressing plunger for compressing depolarizing material in the mold, a perforating plunger for axially perforating the compressed material in the mold, an electrode-inserting plunger for inserting an electrode in such perforation, an ejecting 100 plunger for ejecting the completed electrode from the mold, the plungers and the mold being mounted for relative shifting movement for bringing the plungers successively into register with the mold, and motive 105 means for operating the plungers controlled by such relative shifting movement so that each plunger is operated when it is brought into register with the mold.

3. An electrode-making machine comprising a movable table having a mold therein, a compressing plunger adapted to compress depolarizing material in the mold, a perforating plunger adapted to axially perforate the compressed material, an electrode-inserting plunger adapted to insert an electrode in the perforation, an ejecting plunger adapted to eject the completed electrode from the mold, motive means for the plungers, and means for imparting actuation to 110 the motive means controlled by the movement of the table as the mold is brought into register with the successive plungers.

4. An electrode-making machine comprising a rotative table having four molds therein, four plungers adapted to operate simultaneously upon the material in the respective molds, one plunger being adapted to compress depolarizing material in its mold, the second plunger being adapted to axi- 115 120 125 130 135

ally perforate compressed material in its mold, the third plunger being adapted to insert an electrode in the perforation of the material in its mold, and the fourth plunger being adapted to eject the completed electrode from its mold, motive means for the plungers, and means for imparting actuation to the plungers controlled by the rotation of the table as the molds are successively brought into register with the plungers.

5. An electrode-making machine comprising a rotative table having a plurality of molds therein, a plurality of operating plungers adapted to operate upon the material in the respective molds as the molds are successively brought into register with the plungers by the rotation of the table, a plunger-actuating part, a power-driven part, a part, clutching means for coupling the power-driven part to the plunger-actuating part, and means on the table for operating the clutching means at each time the molds are brought into register with the plungers.

25 6. An electrode-making machine comprising a rotative table having four molds therein, four plungers adapted to operate simultaneously upon the material in the respective molds, one plunger being adapted to compress depolarizing material in its mold, the second plunger being adapted to axially perforate compressed material in its mold, the third plunger being adapted to insert an electrode in the perforation of the material in its mold, and the fourth plunger being adapted to eject the completed electrode from its mold, an actuating crank for the plungers, a power driven member, clutching means for clutching the crank to the power driven member, and means on the table for operating the clutching means as the table is rotated.

7. An electrode-making machine having, in combination, a mold, a compressing plunger for compressing depolarizing material in the mold, a perforating plunger movable toward and away from the mold for perforating the compressed material in the mold, means for bringing the mold successively into register with the compressing and perforating plungers, a closely fitting sleeve extensible to the perforating end of the perforating plunger and slidably backwardly upon the plunger to permit the perforation of the material, and means for yieldingly pressing such sleeve toward the perforating end of the plunger for preventing the breaking of the material by the withdrawal of the perforating plunger from such material after the perforation has been made.

8. An electrode-making machine comprising a rotative table having a plurality of molds therein, a plurality of operating plungers adapted to operate upon the material in the respective molds as the molds are

successively brought into register with the plungers by the rotation of the table, abutment means for stopping the table with the molds in register with the plungers, a plunger-actuating part, a power-driven part, a single rotation clutch for coupling the power-driven part to the plunger actuating part, and means on the table for causing the single rotation clutch to couple the power-driven part to the plunger-actuating part at each step of rotation of the table.

9. An electrode-making machine comprising a mold, a compressing plunger for compressing depolarizing material in the mold, a perforating plunger for axially perforating the compressed material in the mold, an electrode-inserting plunger for inserting an electrode in such perforation, an ejecting plunger for ejecting the completed electrode from the mold, and means for bringing the mold successively into register with the respective plungers in the order recited.

10. An electrode-making machine comprising a plurality of circularly arranged molds, a compressing plunger for compressing depolarizing material in the molds, a perforating plunger for axially perforating the compressed material in the molds, an electrode-inserting plunger for inserting an electrode in each such perforation, an ejecting plunger for ejecting the completed electrodes from the molds, means for supporting the plungers in a circle in concentric alinement with the circularly arranged molds, a rotative mold-supporting table carrying the molds for bringing a corresponding number of the molds into alinement with the respective plungers, and means for operating all of the plungers at once so that each plunger performs its own operation different from that of the other plungers.

11. An electrode-making machine comprising a plurality of circularly arranged molds, a compressing plunger for compressing depolarizing material in the molds, a perforating plunger for axially perforating the compressed material in the molds, an electrode-inserting plunger for inserting an electrode in each such perforation, an ejecting plunger for ejecting the completed electrode from the molds, means for supporting the plungers in a circle in concentric alinement with the circularly arranged molds, a rotative mold-supporting table carrying the molds for bringing a corresponding number of the molds into alinement with the respective plungers so that the plungers will operate successively on the depolarizing material in the respective molds, means for operating all of the plungers at once so that each plunger performs its own operation different from that of the other plungers, handles on the table for imparting forward rotation thereto, abutment means for stopping the table at each step of forward rota-

tion, and movable abutments controlled by the handles for releasing the table to permit it to rotate another step forward.

12. An electrode-making machine comprising a mold, a compressing plunger for compressing depolarizing material in the mold, a perforating plunger for axially perforating the compressed material in the mold, an electrode-inserting plunger for inserting an electrode in such perforation, an ejecting plunger for ejecting the completed electrode from the mold, a mold-supporting table carrying the mold, means for moving the table to bring the mold successively into register with the respective plungers in the order recited, and motive means for operating the plungers controlled by the movement of the table so that each plunger is operated when it is brought into register with the mold; such plunger-operating motive means including a plunger-actuating part, a power-driven part, clutching means for coupling the power-driven part to the plunger-actuating part, and a clutch-operating member carried by the table.

13. An electrode-making machine comprising a plurality of circularly arranged molds, a compressing plunger for compressing depolarizing material in the molds, a perforating plunger for axially perforating the compressed material in the molds, an electrode-inserting plunger for inserting an electrode in each such perforation, an ejecting plunger for ejecting the completed electrodes from the molds, means for supporting the plungers in a circle in concentric alinement with the circularly arranged molds, a rotative mold-supporting table carrying the molds for bringing a corresponding number of the molds into alinement with the respective plungers, and means for operating all of the plungers at once so that each plunger performs its own operation different from that of the other plungers; such plunger-operating means including a plunger-actuating part, a power-driven part, clutching means for coupling the power-driven part to the plunger-actuating part, and a clutch-operating member carried by the table.

14. An electrode-making machine comprising a plurality of circularly arranged molds, a compressing plunger for compressing depolarizing material in the molds, a perforating plunger for axially perforating the compressed material in the molds, an electrode-inserting plunger for inserting an electrode in each such perforation, an ejecting plunger for ejecting the completed electrodes from the molds, means for supporting the plungers in a circle in concentric alinement with the circularly arranged molds, a rotative mold-supporting table carrying the molds for bringing a corresponding number of the molds into alinement with the

respective plungers, and means for operating all of the plungers at once so that each plunger performs its own operation different from that of the other plungers; such plunger-operating means including a rotative plunger actuating part, a rotative power-driven part, a single rotation clutch for coupling the power-driven part to the plunger-actuating part, and a clutch-operating member carried by the table.

15. An electrode-making machine comprising a plurality of circularly arranged molds, a compressing plunger for compressing depolarizing material in the molds, a perforating plunger for axially perforating the compressed material in the molds, an electrode-inserting plunger for inserting an electrode in such perforation, an ejecting plunger for ejecting the completed electrodes from the molds, means for supporting the plungers in a circle in concentric alinement with the circularly arranged molds, a rotative mold-supporting table carrying the molds for bringing a corresponding number of the molds into alinement with the respective plungers so that the plungers will operate successively on the depolarizing material in the respective molds, means for operating all of the plungers at once so that each plunger performs its own operation different from that of the other plungers, handles on the table for imparting forward rotation thereto, abutment means for stopping the table at each step of forward rotation, and movable abutments controlled by the handles for releasing the table to permit it to rotate another step forward; such plunger-operating means including a rotative plunger-actuating part, a rotative power-driven part, a single rotation clutch for coupling the power-driven part to the plunger-actuating part, and a clutch-operating member carried by the table.

16. An electrode-making machine comprising a mold, a compressing plunger for compressing depolarizing material in the mold, a perforating plunger for axially perforating the compressed material in the mold, an electrode-inserting plunger for inserting an electrode in such perforation, an ejecting plunger for ejecting the completed electrode from the mold, means for bringing the mold successively into register with the respective plungers in the order recited, and a yieldable spring-pressed sleeve slidably but snugly surrounding the perforating plunger so as to press upon and prevent the breaking of the compressed material by the withdrawal of the perforating plunger.

17. An electrode-making machine comprising a mold, a compressing plunger for compressing depolarizing material in the mold, a perforating plunger for axially perforating the compressed material in the mold, an electrode-inserting plunger for in-

- 3
19. An electrode-making machine having, in combination, a mold, a compressing plunger for compressing depolarizing material in 35 the mold, a perforating plunger for perforating the compressed material in the mold, means for bringing the mold successively into register with the compressing and perforating plungers, and means for yieldingly 40 operating the compressing plunger in effecting its compressing function.
20. An electrode-making machine having, in combination, a mold, a compressing plunger for compressing depolarizing material in 45 the mold, a perforating plunger for perforating the compressed material in the mold, an electrode-inserting plunger for inserting an electrode in such perforation, an ejecting plunger for ejecting the completed 50 electrode from the mold, means for relatively shifting the mold and the plungers into register in the successive order of the plungers recited, and means for yieldingly operating the compressing plunger in effecting its compressing function. 55
18. An electrode-making machine comprising a mold, a compressing plunger for compressing depolarizing material in the mold, a perforating plunger for axially perforating the compressed material in the mold, an electrode-inserting plunger for inserting an electrode in such perforation, an ejecting plunger for ejecting the completed electrode from the mold, means for bringing the mold successively into register with the respective plungers in the order recited, an electrode-containing hopper, a feed wheel having a plurality of peripheral electrode-receiving grooves, a pawl-and-ratchet device for rotating the feed wheel one step at each operation of the plungers to feed the electrodes from the hopper one at each step, and means for bringing each electrode between 30 and in register with the electrode-inserting plunger and the perforation in the perforated depolarizing material in the mold.

In testimony whereof I have affixed my signature in presence of two witnesses.

SECONDO L. CASELLA.
